UNITED STATES PATENT OFFICE.

PATRICK MURPHY, OF BROOKLYN, NEW YORK.

DESIGN FOR AN ALTAR OR SHRINE.

No. 39,211.

Specification for Design.

Patented March 17, 1908.

Application filed October 29, 1907. Serial No. 399,782. Term of patent 7 years.

To all whom it may concern:

Be it known that I, PATRICK MURPHY, a citizen of the United States, residing at Brooklyn, in the county of Kings and State of New York, have invented a new, original, and ornamental Design for an Altar or Shrine, of which the following is a specification, reference being had to the accompanying drawings, forming a part thereof.

The figure is a perspective view of an altar or shrine showing my new design.

I claim

The ornamental design for an altar or shrine as shown.

PATRICK MURPHY.
